(57) **CLAIM**

The ornamental design for a flip up telescope assembly, as shown and described.

DESCRIPTION

FIG. 1 is a perspective view of the flip up telescope assembly showing our new design;

FIG. 2 is a front plan view;

FIG. 3 is a rear plan view;

FIG. 4 is a right side view;

FIG. 5 is a left side view;

FIG. 6 is a top view; and,

FIG. 7 is a bottom view.

The broken line showing of the spectacles in FIG. 1 is for illustrative purposes only and forms no part of the claimed design.
